CONTROL SYSTEM FOR ELECTRON
DISCHARGE DEVICESJames L. Finch, Patchogue, N. Y., assignor to
Radio Corporation of America, a corporation of
Delaware

Application September 8, 1930, Serial No. 480,445

1 Claim. (Cl. 219—20)

This invention relates to a control system for controlling the flow of current in a system of circuits and especially to one wherein a gas filled triode is used to control the flow of alternating currents.

Heretofore, systems have been devised wherein contacts pass or cut off the flow of current through circuits of a system. Because of the fact that it is sometimes impossible to employ contacts sufficiently large to handle large amounts of power or to control them with sufficient precision, the amount of power that can be provided by this system is limited. In order to use the same contacts and increase the power under control, the contacts are sometimes placed in the control winding circuit of an electromagnetic relay, and sometimes in the control electrode circuit of an electron discharge device whose anode circuit controls an electromagnetic relay. The relay in turn turns on or off, for example, heating current. However, the latter systems have the disadvantages of being complicated and relatively expensive.

A prime desideratum is the removal of the foregoing difficulties; and, to do so it is an object of this invention to provide a system wherein contacts, when open, allow the flow of a considerable amount of working current or power and, when closed, remove the working current or power.

It is a further object of this invention to provide, to act in conjunction with the contacts, an electron discharge device arrangement having a working element in its anode circuit the current through which is turned completely on or off by action of the contacts associated therewith.

Peculiarly adapted for this purpose is the thyratron tube which is an electron discharge device having a disc like anode, a control electrode, a cathode, and, a certain amount of mercury vapor within its container. A negative potential on the control electrode of such a tube is effective in preventing anode current flow despite high anode potentials, but, once anode current flow has been started high negative potentials upon the control electrode or grid are alone ineffective to stop anode current flow. Cessation of anode current can be effected solely by a reduction in anode potential.

As required by statute the present invention is defined in the appended claim. However, it may be best understood both as to its structural organization and mode of operation by referring to the accompanying drawing, wherein,

Figure 1 illustrates a heating system utilizing a single electron discharge device, pulsations of current flowing through a heating element from an alternating source in response to action of contacts opening and closing a control circuit, 69 and,

Figure 2 illustrates a heating system wherein by the use of a plurality of electron discharge devices, a substantially unidirectional current flows through a heating circuit from an alternating current source in accordance with action of operated contacts in a control circuit for opening and closing the same.

Referring to Figure 1, alternating heating energy is supplied to an electron discharge device, 70 such as a thyratron, from an energy input circuit 2 through a primary 4 of a transformer 6 having as shown, a split secondary 8. Heating energy is taken from a portion of the secondary winding 8 through conductors 10 to the cathode 75 12 of electron discharge device 14. To establish an electrical balance, a conductor 16 is connected from the primary winding 4 of transformer 6 to the midpoint of potentiometer 18 connected across cathode 12. 80

A control circuit, formed by the secondary winding of transformer 6, temperature responsive contacts 20 and impedance 22 preferably in the form of a high resistance is connected across the input terminals of the electron discharge device 14. 85

The output circuit of electron discharge device 14, comprising a heating or working element in the form of a resistance 24 is used for the purpose of maintaining a compartment and the apparatus therein, (not shown) at a constant temperature. Anode potential is supplied to the anode 26 of the electron discharge device 14 through heating element 24 and conductor 28 leading to the primary winding 4 of transformer 6. 95

The control electrode 30, of electron discharge device 14, with contacts 20 open, is supplied with alternating potentials from the secondary 8 of transformer 6 in phase with the potentials supplied to the anode 26. Consequently, during alternating half cycles of the input energy, when anode 26 and grid 30 are rendered positive, working current pulsations will flow in the output circuit increasing the temperature of the compartment about and for apparatus close to resistance element 24. 100

Upon reaching a desired temperature, contacts 20, which also are in close proximity to the elements to be maintained at constant tem- 110

perature, will close as a result of which, the potentials applied to the control electrode 30 are effectively reversed in phase, since the energization of the control circuit with the contacts 5 closed is such that current flowing through high resistance 22 will engender potentials on control electrode 30 out of phase with those on the anode 26. Therefore, no longer will there be anode current flow and consequently, heating 10 action, until the ambient temperature of contacts 20 drops to a value such that contacts 20 open thereby allowing of the in phase potential excitation of anode 26 and control electrode 30.

In order to increase the energy output, a plurality of tubes such as tube 14, may be paralleled, similar electrodes being paralleled together.

The circuit, moreover, may not only be used in connection with a temperature controlled system, but, contacts 20 may be opened and closed in any desired fashion, for example, in response to fluid flow, in which case the voltage drop across the element 24 may be utilized for the purpose of controlling apparatus to control the 25 fluid flow in desired fashion.

In order to make the output or working energy flow more nearly continuously, as well as to increase the same, the arrangement shown in Figure 2 may be used to good advantage. Electron discharge devices 32, 34 have their anodes connected serially through secondary winding 36 of transformer 38 supplied with energy from a suitable energy input circuit 40. The cathodes of devices 32, 34 are connected together and 30 energized in any suitable fashion such as by an energizing transformer 42.

The control electrodes of the tubes are connected together through impedances 44, 46 preferably resistances. The anode circuit is completed from the midpoint of secondary 36 through conductor 48, element 50 to the midpoint of the secondary of transformer 42, which is at a zero alternating current potential point.

The control circuit 52 is connected across the 45 impedances 44, 46 such that with contacts 54 closed, the alternating potentials applied to the control electrodes or grids and anodes or plates of each of the tubes 32, 34 are out of phase. With contacts 54 open, the potentials applied to 50 the grid and plate of each tube are in phase allowing current flow therethrough. Consequently, it should be clear that with contacts 54 open, representing a cold condition, rectification of input energy from input circuit 40 will

55

occur and current will flow in the output or working circuit, or, through heating element 50.

Upon reaching a desired, predetermined temperature, the temperature responsive contacts 54 will close, as a result of which energy fed from source 40 into the secondary 56 of transformer 38 will cause potential variations across impedances 44, 46 such that the control electrodes of the tubes will shift in potential 180 degrees out of phase with the potentials on their cooperating anodes. Current flow through the heating element 50 will consequently cease.

As stated in connection with Figure 1, the tubes 32, 34 may be paralleled by suitable similar tubes in order to increase the output, contacts 54 may be actuated in any desired fashion, and, the current flow through resistance 50 may be utilized in any desired fashion rather than solely for heating purposes.

Having thus described my invention, what I claim is:

Temperature control apparatus having, in combination, a pair of gas filled electron glow discharge devices, each having anode, cathode and control electrodes, a first transformer having a single primary winding and two secondary windings, a source of alternating potential across said primary winding, the anodes of both said devices being serially coupled through one of said secondary windings, the control electrodes of said devices being coupled through two serially arranged high resistances, means for heating the cathodes of said devices comprising a source of potential coupled to said cathodes through a second transformer the secondary of which is coupled across said cathodes in parallel, a connection including a serially arranged heater circuit from a point intermediate the ends of said one secondary winding of said first transformer to said cathodes, and a connection from a point intermediate said two high resistances to said cathodes, a pair of contacts thermostatically controlled, one of said contacts being connected to one of said control electrodes and the other of said contacts being connected to one side of said other secondary winding of said first transformer, the other side of said last secondary winding being connected to said other control electrode whereby potentials applied to said control electrodes are in phase with potentials applied to said anodes when said contacts are open and out of phase when said contacts are closed.
